(57) **CLAIM**

The ornamental design for the shopping trolley, as shown and described.

DESCRIPTION

FIG. 1 is a front and side perspective view of a shopping trolley showing my new design;

FIG. 2 is a front view thereof;

FIG. 3 is a rear view thereof;

FIG. 4 is a side view thereof, the opposite side view being the mirror image of FIG. 4;

FIG. 5 is a top view thereof; and,

FIG. 6 is a bottom view thereof.

The broken lines shown in FIGS. 1, 2, 5 and 6 are shown to represent stitching.

1 Claim, 5 Drawing Sheets
